UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

ELECTRIC SWITCH.

1,413,156.

Specification of Letters Patent. Patented Apr. 18, 1922.

Application filed July 10, 1919. Serial No. 309,853.

To all whom it may concern:

Be it known that I, GEORGE A. BURNHAM, a citizen of the United States, residing at Saugus, in the county of Essex and 5 State of Massachusetts, have invented an Improvement in Electric Switches, of which the following is a specification.

My invention relates to electric switches and has more particular reference to a 10 switch having a high circuit interrupting capacity.

The circuit interrupting capacity of an electric switch, by which is meant the capacity of the device to safely interrupt 15 a circuit at normal voltage and after such interruption be in condition for further service, depends largely upon the dimensions of the switch, the physical strength of the materials composing the switch and 20 upon the ability of the device to prevent the discharge therefrom of heated gas and oil caused by the relatively great pressures momentarily existing within the switch due to the arc formed upon interruption of the circuit.

Heretofore it has been customary to construct the switch substantially air tight and depend upon the strength of the materials comprising it to resist the relatively 30 great pressures which may be developed therein, or provide a relief means, as a gas relief valve, to relieve pressure within the switch above a certain value. With this arrangement, the switch may not become 35 damaged but oil is violently thrown from the vent and deposited upon surrounding circuit leads and other objects and, if the oil is on fire when expelled, the burning oil is scattered in all directions. As a remedy 40 it has been customary to install relatively large switch structures to provide for a considerable gas expansion space with the result that the switching equipment occupies a considerable portion of the total space 45 in a station.

An object of my invention is to provide a switch having relatively moderate dimensions and relatively great strength whereby it may the more successfully resist internal 50 pressures due to circuit interruption without permanent distortion or failure of any of its components.

This object is attained by designing the

switch components with particular regard for the stresses to which they are subjected during the interruption of the circuit.

A further object of my invention is the provision of means whereby upon the development of an abnormal pressure within 60 the switch the expansion space or the volume above the level of the oil contained therein may be automatically and relatively largely increased whereby to provide, in effect, a large expansion chamber, to thereby 65 maintain at a low value the pressure resulting from the circuit interruption.

This object is attained by yieldingly suspending the oil receptacle from the switch frame, whereby, upon abnormal pressure 70 developed therein, it is caused to move downward to thereby increase the expansion volume of the switch and reduce the maximum developed pressure, and also to absorb energy developed upon circuit interruption. Upon the reduction of pressure 75 the receptacle is automatically restored to its normal position.

Due to the heat of the arc the oil or the vapor within the switch is heated to a relatively high degree and unites with the air contained in the expansion chamber above the oil and burns, or at least it is heated to such a high degree that when it is expelled from the switch it combines with 80 the air and burns, and the result is a discharge of a mass of flame from the switch which may result in the destruction of the station.

A further object of my invention, therefore, is to provide means for cooling the heated gas and oil previous to their discharge from the switch whereby, upon issuance therefrom the temperature is so low 90 that it will not burn.

A yet further object is to retain the discharged and condensed vapor or oil from the switch in a convenient receptacle having means for indicating the amount of oil collected whereby the efficiency of operation 100 of the switch may be made known.

These objects of my invention are attained in the provision of a relatively narrow discharge passage or vent extending from the expansion space above the oil into 105 an oil collecting reservoir. The passage,

while narrow, is of relatively great extent whereby a large area of passage is provided, and the walls of the passage are formed of good heat conducting materials, 5 whereby, upon the discharge of flame or hot vaporized oil from the switch, the heat thereof is abstracted by the relatively cold heat conducting walls whereby the flame is quenched and the vaporized oil is condensed. The vaporized oil collects in the oil collecting reservoir and the condensed or relatively cold gases or vapor escape from the open top of said reservoir.

Fig. 1 is a side elevation of a switch 15 embodying my invention.

Fig. 2 is a sectional elevation along lines 2—2 of Fig. 1.

Fig. 3 is a sectional detail of the tank suspending means in an operated position 20 thereof.

Fig. 4 is a partial plan view of the switch of Fig. 1.

Fig. 5 is a plan view of a supporting grid for the oil receptacle.

25 As here shown, my invention is applied to the switch having stationary switch members 10 depending from the switch frame 11, which frame is provided with the bracket 12 integrally formed or otherwise associated therewith by which the switch is secured to a fixed supporting member 13. A movable switch member including the brush member 14 is arranged to contact with the stationary switch members and a rod 15 extends therefrom through said frame 11 to which is secured the switch operating mechanism 16 including guide links whereby an approximately straight line motion of the movable switch member is obtained.

40 The switch frame includes a top-portion 17 which forms a cover for the oil receptacle. Said top-portion is substantially concave in cross section whereby the better to resist internal pressures developed upon the opening of the circuit by the switch. A plurality of ribs 18 are formed thereon to also strengthen the frame, which ribs merge into the flange 19 which extends about the outer edge of the frame. A depending flange or apron 20 extends from the outside of the top-portion 17 down for a considerable distance say, approximately one third the way down, around the oil receptacle 21 and is provided with a plurality of ribs 20^a by 55 which said apron is strengthened.

It has heretofore been common to provide the switch frame with a lip or depending flange which is extended downward below the top of the oil receptacle for a short distance, say one half inch. This lip, while normally serving the more effectively to close the top of the oil receptacle, serves no useful purpose in laterally supporting the walls of the oil receptacle in the event of 60 its distortion by the pressures developed

within the switch at the instant of circuit interruption; it being found that the oil receptacle would bulge at its sides and the top of the receptacle would be drawn down below and beyond the flange.

70 By the provision of the apron 20 extending downward over the side of the oil receptacle, as shown in the drawings, any force tending to distort the oil receptacle serves merely to force the walls thereof against 75 said apron by which the force is resisted and further outward movement of said walls is prevented. Upon the return of pressure to normal, the receptacle, due to its inherent elasticity, returns to its normal shape and it is thereby unaffected by the pressure rise.

Fig. 1 is a side elevation of a switch 80 embodying my invention. The switch is provided with two oil receptacles; the inner tank 21, and the outer or oil receiving reservoir 22. Said receptacles are spaced one within the other and 85 preferably secured together at the bottom thereof by suitable means, as by spot welding. The inner tank 21 comprises the usual oil receptacle for the switch and contains the movable and stationary switch members. 90 Said receptacle is slightly smaller than the space bounded by the depending apron 20 and centrally spaced therein whereby there is a relatively narrow passage between said receptacle and said apron down which gas 95 and oil is adapted to pass upon the opening of the switch under abnormal current conditions. The outer tank 22 having an open top is spaced from the inner tank and the apron 20 preferably extends downward for 100 a substantial distance or into the space between said tanks to thereby guide the oil thrown from the inner tank into the outer tank. An oil gauge 23 communicates with said outer tank and serves to conveniently 105 indicate the amount of oil contained therein.

The yielding supporting-means for the oil receptacles includes the side-rods 25 which are arranged in pairs on opposite sides of the receptacles. Said rods are secured to separate grids 26, or it may be one grid, and extend upwardly and pass through lugs 27 carried by the switch frame 11. Said lugs are formed with the spring receiving recesses 28 therein in which the coil 115 springs 29 encircling said rods 25 are arranged and nuts 30 adjustably threaded on said rods 25 transmit the weight of the receptacle to said springs. The tension of said springs or the point at which said tank 120 will be moved downward by the circuit interruption pressure may be governed by varying the position of said nuts 30 on said rods. Stop collars 31 are fixed to said rods beneath said lugs 27 to limit the upward 125 movement of said receptacle due to the springs whereby a slight amount of clearance may be provided between the top of the inner receptacle and the inner sides of the switch frame.

Under normal conditions of switch operation said springs 29 serve to retain the oil receptacle at its highest position or substantially in contact with the switch frame.

5 Upon the development of any considerable pressure within the switch from the interruption of the circuit controlled thereby, such increase of pressure serves to overcome the tension of the springs and causes the receptacle to be forced downward away from the switch frame whereby the volume of the expansion chamber above the body of the oil is increased and may be increased in proportion to the increase of pressure, whereby 10 the development of a large and destructive value of pressure within the receptacle may be obviated and energy developed within the switch is absorbed because of such movement.

20 The side walls of the inner oil receptacle 21 are adapted to be spaced from the apron 20 by a relatively small distance, as indicated at 35 whereby to provide a communicating passage between the expansion space between 25 the switch frame and the top of the oil within the receptacle and the outside of the switch. Although the space is adapted to be relatively narrow, yet due to its length, the actual area of passage is relatively great 30 whereby a relatively unrestricted discharge of heated gas and vaporized oil from the interior of the switch may take place. Because of the narrowness of said passage 31 all of the heated gas and vaporized oil discharged 35 from the switch is brought into close and intimate contact with either said apron or said walls of the oil receptacle 21 and, due to contact with said relatively cool walls, become in themselves cooled, and the extent 40 of the cooling is designed to be such that any flame which may be present within the switch is quenched before its exit therefrom and the vaporized oil is cooled and may be condensed, or at least its temperature is so lowered that it cannot combine spontaneously 45 with the oxygen in the air whereby the discharge of a flame from the switch is prevented. Condensed oil vapor collects within the oil collecting receptacle 22 as does also 50 the oil which, while not in a state of vapor has been violently expelled from the oil receptacle upon the opening of the switch. The space between the outer receptacle 22 and the inner receptacle 21 also aids, by reason 55 of the confined air space therebetween and the cooling effect of the side walls thereof, in so reducing the temperature of the gases and vapors discharged from the switch that no flame issues from the switch upon 60 the interruption of an abnormal value of current. Furthermore, the space between the two receptacles is relatively narrow as contrasted with its depth, so that combustion cannot be maintained therein.

65 It will be seen that the arrangement above

set forth results in an electric switch having relatively moderate physical dimensions with relatively great interrupting capacity. The term "oil" is herein used generically to denote any insulating or arc-quenching fluid. 70

I claim:—

1. An electric switch comprising a fixed support for the stationary and movable switch members, and a fluid receptacle enclosing the switch members resiliently and 75 removably carried by said support.

2. An electric switch comprising a fixed switch-supporting frame, stationary and movable switch members carried thereby and depending therefrom, and a receptacle 80 removably and yieldingly disposed about said switch members adapted to contain a fluid in which said switch members are immersed.

3. An electric switch comprising a fixed switch-supporting frame, stationary and 85 movable switch members carried thereby, a fluid receptacle depending from said frame cooperating therewith to enclose a gas expansion space above the fluid therein under said frame, and means removably to secure 90 said receptacle yieldingly to said frame.

4. An electric switch comprising a fixed switch-supporting frame, stationary and movable switch members carried thereby and depending therefrom, and a receptacle yielding disposed about said switch members adapted to contain a fluid in which said 95 switch members are immersed.

5. In an electric switch, the combination of a fixed switch-supporting frame comprising a cover, switch members carried thereby, an apron arranged to downwardly deflect the gas expelled from the switch depending from said cover, a depending fluid receptacle having an open top inclosed within said 100 apron and peripherally spaced therefrom to afford free egress for gases, and means including springs removably to hold said receptacle yieldingly in the aforesaid relation with said cover and apron, said receptacle 105 and cover cooperating to form an expansible gas and air space, and said yielding suspension providing means to vary the volume of said space.

6. In an electric switch, the combination of a fixed frame comprising a cover, fixed and movable switch members mounted in said cover, an apron depending from said cover, a fluid receptacle having an open top, enclosed within said apron and peripherally spaced therefrom to afford free egress for gases, and means, including springs, to hold the receptacle yieldingly in the aforesaid relation with the cover and apron; the receptacle and cover providing an expansible air and gas space, and the yielding suspension providing means to vary the volume of said space without affecting the relationship of the fixed and movable switch members. 115

7. In an electric switch, the combination of a fixed frame comprising a cover, an apron depending from said cover; a fluid receptacle having an open top, enclosed within said apron and peripherally spaced therefrom to afford free egress for gases, and means including springs, to hold the fluid receptacle yieldingly in the aforesaid relation with the cover and apron, and an outer receptacle, having its walls extending to and surrounding the cover-apron, and spaced therefrom to provide a final vent for gases at least as ample as the passage between the oil receptacle and said apron.
8. In an electric switch, the combination of a fixed switch-supporting frame, stationary and movable switch members carried thereby, a receptacle adapted to contain a fluid in which said switch members are immersed, a grid upon which said receptacle is received, rods extending from said grid through apertures in said frame, and springs encircling and engaging said rods and said frame, whereby yieldingly to depend said receptacle from said frame.
9. An electric switch comprising a switch frame having recessed lugs, a receptacle, rods associated with said receptacle extending through said lugs, spring-tension adjusting means carried by said rods, and springs arranged in the recesses of said lugs engaging said adjusting means and switch frame.
10. An electric switch comprising a switch frame having recessed lugs, a receptacle, a grid supporting said receptacle, rods extended from said grid through said lugs, spring-tension adjusting means carried by said rods, and springs arranged in the recesses of said lugs yieldingly supporting said receptacle through said adjusting means from said switch frame.
11. An electric switch comprising a fixed switch frame, and a receptacle for fluid removably depending therefrom, said switch frame having a peripheral flange surrounding and closely spaced from the side-walls of said receptacle to provide a gas cooling passage therebetween and depending a substantial distance down the side-walls thereof, whereby also to support the receptacle against lateral distortion due to internal pressure at the top of the side-walls and also for a considerable distance below the top thereof.
12. An electric switch comprising an inner receptacle, an outer receptacle adapted to contain a fluid, a switch frame comprising a cover for the inner receptacle, means supporting said receptacles from said switch frame, the side-walls of said receptacles spaced from each other, said cover having a peripheral flange spaced from the side-walls of said inner receptacle and depending downwardly over said side-walls whereby to downwardly guide fluid expelled from the inner receptacle into the outer receptacle.
13. An electric switch comprising an inner receptacle adapted to contain a fluid, an outer receptacle containing said inner receptacle, a switch frame, means supporting said receptacles from said switch frame, the side-walls of said receptacles spaced from each other, said switch frame having a peripheral flange spaced from the side-walls of said inner receptacle and depending over said side-walls into said outer receptacle whereby to guide fluid expelled from the inner receptacle into the outer receptacle.
14. An electric switch comprising an inner receptacle adapted to contain a fluid, movable and stationary switch members contained therein, a switch frame having a peripheral flange depending over the side-walls of said receptacle and spaced therefrom to provide a vent for the switch, an outer receptacle containing said inner receptacle having side-walls extended above said flange and having an open top whereby to collect fluid discharged from said inner receptacle, and means to secure said receptacles to said switch frame.
15. An electric switch comprising an inner receptacle adapted to contain a fluid, movable and stationary switch members contained therein, a switch frame comprising a cover having a peripheral flange depending therefrom over the side-walls of said receptacle and spaced therefrom to provide a vent for the switch, an outer receptacle containing said inner receptacle having an open top and side-walls extended upward toward said flange whereby to collect fluid discharged from said inner receptacle, and means removably to secure said receptacles to said switch frame.
16. An electric switch comprising an inner receptacle adapted to contain a fluid, movable and stationary switch members contained therein, a switch frame comprising a cover having a peripheral flange depending therefrom over the side-walls of said receptacle and spaced from said side walls to provide a vent for the switch, an outer receptacle containing said inner receptacle having an open top and side-walls extended upward toward said flange whereby to collect fluid discharged from said inner receptacle, and means removably and yieldingly securing said receptacles to said switch frame.
17. An electric switch comprising in combination a fixed switch-supporting member comprising a cover, stationary and movable switch members carried thereby, an outer receptacle, an inner receptacle contained in said outer receptacle having its side-walls peripherally spaced from said outer receptacle, said inner receptacle arranged to contain a fluid in which said switch mem-

bers are immersed, and vent into said outer receptacle, and means removably to secure said receptacles yieldingly to said frame.

18. In an electric switch, the combination 5 of a fixed switch-supporting frame comprising a cover, switch-members carried thereby, an apron arranged to downwardly deflect the gas expelled from the switch depending from the cover, a depending fluid receptacle having an open top enclosed within 10 said apron and peripherally spaced therefrom to afford free egress for gas, and means to hold said receptacle yieldingly in the

aforesaid relation with said cover and apron, said receptacle and cover cooperating to 15 form an expansible gas and air space, and said yielding suspension providing means to vary the volume of said space.

In testimony whereof, I have signed my name to this specification, in the presence of 20 two subscribing witnesses.

GEORGE A. BURNHAM.
